UNITED STATES PATENT OFFICE.

JOSEPH ARENSEN, OF CHICAGO, ILLINOIS.

INSIDE COAT-POCKET.

1,076,260.

Specification of Letters Patent.

Patented Oct. 21, 1913.

Application filed January 24, 1912, Serial No. 673,176. Renewed May 24, 1913. Serial No. 769,763.

To all whom it may concern:

Be it known that I, JOSEPH ARENSEN, a subject of the Emperor of Russia, and a resident of the city of Chicago, county of Cook, and State of Illinois, have invented 5 certain new and useful Improvements in Inside Coat-Pockets, of which the following is a specification.

My invention relates to improvements in 10 pockets and more specifically to improvements in an inside coat pocket in which is provided a supplemental pocket or compartment for the reception of a pencil or the like.

15 The object of my invention is the production of a pocket of the character mentioned which will be of improved construction, one which may be provided in a coat with ease and expedition and hence at a low cost, 20 and one which will be of neat and finished appearance and efficient in use.

Other objects will appear hereinafter.

With these objects in view, my invention 25 consists in the combinations and arrangements of parts hereinafter described and claimed.

My invention will be best understood by 30 reference to the accompanying drawings forming a part of this specification, and in which—

Figure 1 is a fragmentary view of a coat lining showing the first step employed in the application of a pocket thereto embodying my invention, Fig. 2 is a cross section of 35 the construction shown in Fig. 1, except that the layer or portion which is attached to the lining and which is shown in upright position in Fig. 1, is shown folded down in Fig. 2, this being the next step in the construction of the pocket, Fig. 3 is a view 40 similar to Fig. 1, illustrating the next step in the construction of the pocket, Fig. 4 is a section similar to Fig. 2, illustrating the step succeeding that illustrated in Fig. 3, Fig. 5 is a view similar to Figs. 1 and 3, 45 illustrating the step following that shown in Fig. 4, Fig. 6 is a cross section thereof, Fig. 7 is a fragmentary front view of the coat lining showing the completed pocket 50 arranged therein, and Figs. 8 and 9 are sections taken on substantially lines $\alpha\alpha$ and yy of Fig. 7.

The preferred form of construction, as 55 illustrated in the drawings, is shown ap- plied to a coat the lining of which is illus- trated at 1. The pocket which is formed

in this lining and which constitutes the subject matter of this invention, comprises inner and outer layers 2 and 3 which are sewed together, as shown, at their peripheries except the outer edges thereof which are sewed to the lining 1 at 4 and 5 respectively, the mouth or upper edge of the pocket registering with a slit 6 which is provided in said lining. The supplemental 60 pocket is formed by a narrow layer 7 which is secured at its periphery to the front side of the layer 2, the upper edge of the layer 7 being stitched or sewed, as at 8, to the lining 1, the stitching 8 being positioned below the stitchings 4. In order to gain 65 access to the supplemental pocket the stitchings 4 closing the mouth of the said supplemental pocket are removed, as shown in Figs. 7 and 8.

75 In the construction of the pocket the layer 2 is first secured to the lining 1 by stitchings 4, as clearly shown in Fig. 1. The layer 2 is then bent upon itself, as shown in Fig. 2, and the supplemental layer 7 secured by 80 stitchings 8 with the edge thereof to be attached, disposed in close proximity with and parallel to the attached edge of layer 2, as shown in Fig. 3. Layer 7 is then folded upon itself, as shown in Fig. 4, whereupon 85 the layer 3 is secured to the lining 1 by stitchings 5 with its edge to be attached arranged in close proximity to and parallel with the attached edges of layers 2 and 7. The slit 8 is then formed in the lining 1 90 disposed intermediate the adjacent edges of layers 3 and 7 and 2, as shown in Figs. 5 and 6. Next, the layers 2, 3 and 7 are forced through the slit 6 to the dotted line position shown in Fig. 6, whereupon the 95 edge 9 of layer 7 is sewed to the layer 2. The layers 2 and 3 are then arranged with their peripheries registering, whereupon the same are sewed together, as shown, it being seen that in this stitching of the layers 2 and 100 3 together, the remaining lower and longitudinal edges of the layer 7 will be also secured to the layer 2 by the same stitching as connects said layer 2 with the layer 3, as shown in Fig. 7. The stitching 4 at the 105 mouth of the supplemental pocket is then removed as by cutting through the employment of a knife, this operation completing the formation of the pocket.

A pocket constructed as set forth may be 110 formed with expedition and hence at a low cost. A main pocket is thus provided to

gether with a supplemental pocket, the supplemental pocket being entirely independent of the main pocket. It is the practice at the present time, in the formation of a supplemental pocket in an inside coat pocket, to run a line of stitching vertically through the walls of the pocket adjacent one edge, thus forming a supplemental or pencil pocket at one edge of the main pocket. With this practice, however, it will be seen that the main pocket is decreased in dimensions or in width an extent equal to the width or dimensions of the supplemental pocket formed, this being objectionable in that the resulting main pocket is decreased in size to such an extent as to be inadequate to serve the purposes for which it is designed. In the present case this objection is overcome, by providing a supplemental pocket within the main pocket without altered size thereof. The resulting construction is neat and finished in appearance, the presence of a supplemental pocket being unnoticeable from without; and by extending the upper edge of the layer 2 of the main pocket above the lower edge of the slit, as shown, the gaining of access to the supplemental pocket is evidently facilitated.

While I have illustrated and described the preferred form of construction for carrying

my invention into effect, this is capable of variation and modification without departing from the spirit of the invention. I, therefore, do not wish to be limited to the exact details of construction set forth, but desire to avail myself of such variations and modifications as come within the scope of the appended claim.

Having described my invention, what I claim as new and desire to secure by Letters Patent, is:

The combination with a sheet of material having a slit formed therein; of layers of material attached to the sides of said slit, one of said layers being so attached that the upper terminal thereof projects above the lower side of the slit aforesaid; stitching connecting the peripheries of said layers; and a narrowed supplemental strip attached to the outer surface of one of said aforementioned strips constituting a supplemental pocket, the opening of which is disposed below the lower side of the slit aforesaid.

In testimony whereof I have signed my name to this specification in the presence of two subscribing witnesses.

JOSEPH ARENSON.
